CLAIM

The ornamental design for an insulin syringe injector with auto-aspirator, substantially as shown and described.

DESCRIPTION

FIG. 1 is a perspective view of an insulin syringe injector with auto-aspirator embodying my new design;

FIG. 2 is a top plan view thereof;

FIG. 3 is a side elevational view thereof;

FIG. 4 is an end elevational view thereof as viewed from the left of FIG. 3;

FIG. 5 is an end elevational view thereof as viewed from the right of FIG. 3;

FIG. 6 is a bottom plan view thereof;

FIG. 7 is a side elevational view thereof as viewed from the opposite side of FIG. 3.
